United States Patent Office

Des. 194,037
Patented Nov. 13, 1962

194,037

TABLE OR THE LIKE

Richard G. Reineman, Covina, Calif., and George E. Schaefer, Muskegon Heights, Mich., assignors to Brunswick Corporation, a corporation of Delaware

Filed Apr. 6, 1960, Ser. No. 60,068

Term of patent 14 years

(Cl. D33—14)

Fig. 1

Fig. 2

FIG. 1 is a side elevational view of a table or the like showing our new design; and

FIG. 2 is a bottom plan view thereof.

The dominant features of the design are shown in full lines in the drawings.

The pedestal of the table shown is circular.

We claim:

The ornamental design for a table or the like, substantially as shown and described.
